(57) **CLAIM**

The ornamental design for a retention connection extrusion for a pinch sensor, as shown and described.

DESCRIPTION

FIG. 1 is a perspective view of a retention connection extrusion for a pinch sensor, in accordance with the present invention;

FIG. 2 is a front elevation view thereof, shown in a condition of use;

FIG. 3 is a front elevation view thereof;

FIG. 4 is a right side elevation view thereof;

FIG. 5 is a bottom plan view thereof;

FIG. 6 is a left side elevation view thereof;

FIG. 7 is a top plan view thereof;

FIG. 8 is a rear elevation view thereof;

FIG. 9 is a perspective view of a retention connection extrusion for a pinch sensor, in accordance with a second embodiment of the present invention;

FIG. 10 is a front elevation view thereof, shown in a condition of use;

FIG. 11 is a front elevation view thereof;

FIG. 12 is a right side elevation view thereof;

FIG. 13 is a bottom plan view thereof;

FIG. 14 is a left side elevation view thereof;

FIG. 15 is a top plan view thereof; and,

FIG. 16 is a rear elevation view thereof.

Portions of the article between the symbolic break lines form no part of the claimed design.

The dash-dash broken lines depicting symbolic break lines show boundary lines which form no part of the claimed design. The dash-dash broken lines in FIGS. 2 and 10, illustrate environmental structure which forms no part of the claimed design.
